UNITED STATES PATENT OFFICE

WILLIAM D. LANE, OF OMAHA, NEBRASKA, ASSIGNOR TO EGGERSS-O'FLYNG COMPANY,
OF OMAHA, NEBRASKA, A CORPORATION OF NEBRASKA

SHIPPING CONTAINER FOR LIVE CHICKS

Application filed October 24, 1927. Serial No. 228,347.

My invention relates to the general class of shipping containers and particularly to containers for the shipment of live chicks by express and parcel post. It is the object of my 5 invention to provide an efficient and inexpensive shipping container, having ventilated compartments therein for the chicks, and having means enabling a plurality of the containers to be stacked one upon another without interfering with the ventilation of the compartments. The problem to which my 10 invention offers an effective and satisfactory solution, relates especially to the poultry raising industry, in which there has been a 15 marked tendency in recent times toward the centralizing of incubation in large hatcheries, which may be operated efficiently by persons especially skilled therein, and from which the young chicks are distributed to locations 20 where they are to be raised. The shipment of young chicks for considerable distances by express and parcel post is entirely practicable by reason of the fact that for approximately 25 seventy hours after hatching the chicks require neither food nor water, but merely the maintenance of suitable temperature to prevent chilling, a suitable supply of fresh air, and sufficient separation to prevent piling and smothering of some of the chicks 30 by the others of the assemblage. To facilitate the control of temperature conditions it is desirable that the containers used for shipment thereof be of such capacity as to accommodate 35 large numbers of the chicks, whereby the natural warmth of their bodies may be combined to prevent chilling. It is also desirable that the containers be relatively light in weight, while having, of course, sufficient 40 strength to resist crushing or deformation. The placing of a large number of the chicks in a single container requires the provision of 45 means for separation or segregation thereof into groups, each containing small enough number of the chicks to avoid piling and smothering. For convenience of handling during transportation, it is desirable also that the shipping container be of such construction that a plurality thereof may be placed in a stack or pile, or, where shipment thereof is 50 made to a common destination, a plurality of

the containers secured together to form a single package and be handled as a unit.

The above mentioned qualifications are all embodied in the shipping containers constructed in accordance with my invention and 55 illustrated in the accompanying drawings, in which Fig. 1 is a perspective view of a shipping container embodying my invention, and Fig. 2 is a side view of one of the containers, having a second container superposed 60 thereon, the latter being in transverse vertical section.

In the preferred embodiment of my invention the container is made throughout from corrugated fiber-board, a material 65 which is of light weight proportionally to its strength, and which also has relatively high heat-insulating qualities. The container has a box-like rectangular body-portion comprising a flat bottom 5 and vertical 70 sides 6, the latter having horizontal rows of perforations 7 spaced intermediate their upper and lower edges. For the open top of the body-portion there is provided a removable cover comprising the flat sheet 8, having 75 downwardly turned edge portions 9 adapted to fit over the edges 6 of the body. The cover 8 has therein rows of perforations 10 arranged as shown, and also has the longitudinal and transverse slots 11, each extending 80 from a point near the edge-portions 9 to a point near the center at which the slots would intersect if prolonged. The space within the container is divided longitudinally 85 and transversely by vertical partition-sheets 12 of which the laterally bent ends 13 are suitably secured to the sides 6 of the body, the central parts of the partition-sheets being reversely notched and interengaged with each other, similarly to the strips used in 90 forming fillers for egg-crates. The slots 11 in the cover are so arranged that when the cover is in place upon the body-portion of the container, said slots are aligned respectively 95 with the transverse and longitudinal partition-sheets, and the latter are provided at their upper edges with rectangular extended portions 14 which project through the slots and terminate in a common horizontal plane above the cover. The partition-sheets are so 100

cut from the corrugated fiber-board that the corrugations thereof extend vertically. By reason of the extended portions 14 fitting within the slots 11, the cover-sheet supports the same laterally and prevents deflection laterally of the partition-sheets and said extended portions 14. In consequence of the described structure, said extended portions 14 are capable of supporting upon their upper edges a relatively large weight, thus enabling a plurality of the containers to be placed in superposed relation, the bottom 5 of one resting upon the edges of the partition-extensions 14 of the one beneath, as shown in Fig. 2, and the cover 8 of the lower container is thus sufficiently spaced from the bottom of the superposed container to allow the efficient ventilation of the compartments of the lower container by circulation of air 20 which enters at the perforations 7 in the sides 6 and emerges through the perforations 10 in the cover 8. A plurality of the superposed containers may be secured together by merely binding the same with cords, and thereby 25 formed into a single package for convenience of handling when the several containers have a common destination.

In a container such as illustrated, the height may be approximately six inches, and 30 the length and breadth between eighteen and twenty-four inches. In a container of such size, the division thereof by partitions into four compartments makes each compartment of such size that the chicks therein are not 35 liable to injury by piling and smothering, and each compartment is amply ventilated by the air-inlet perforations 7 at the sides thereof and the perforations 10 at the top. The inner sides of the compartments, formed 40 by the partitions, will be warmed by the body-heat of the chicks, and the latter will instinctively assemble along said inner sides when the exterior temperature is lowered, or, when the temperature is raised, move toward 45 the cooler outer sides of the compartments, being thereby also more nearly in the path of the air circulating between the perforations 7 and 10.

Now, having described my invention, what 50 I claim and desire to secure by Letters Patent is:

1. In a structure of the class described, the combination with the container having bottom, sides and removable cover, of vertical 55 partitions secured intermediate the sides and dividing the inclosed space into a plurality of compartments, said partitions having portions extended through slots in the cover, said extended portions of the partitions having upper edges lying in a common plane above and spaced from the cover, and the sides and cover being perforate to enable circulation of air through the several compartments.

2. A shipping container for live chicks, 65 comprising a box having a rectangular body-

portion, a removable cover, and partitions extending transversely between opposite sides of the body-portion, the cover and sides of the body-portion having ventilating perforations therein, the cover having therein slots aligned vertically with the partitions, and the partitions having portions extended through said slots and terminating at a common level above the cover, whereby to comprise spacing supports when a plurality of the containers are superposed.

3. A structure as set forth in claim 2, in which the partitions are formed by corrugated fiber-board having the corrugations of the sheets extending vertically.

4. A shipping box for chicks including partitions in said box having portions projecting through the walls of the said box for spacing other articles therefrom when in use.

5. A shipping box including bottom, top and side walls, some of said walls having ventilating apertures therein and spacing members extending from within the box through at least one of said walls and projecting outwardly therefrom for spacing said box from other articles placed adjacent thereto when in use.
